CLAIM

An ornamental design for a pole climbing and fall restraint device, as shown and described.

DESCRIPTION

FIG. 1 is a perspective bottom view of the pole climbing and fall restraint device;

FIG. 2 is a front view of the pole climbing and fall restraint device positioned around a pole;

FIG. 3 is a back view of the pole climbing and fall restraint device positioned around a pole;

FIG. 4 is a left side view of the pole climbing and fall restraint device positioned around a pole;

FIG. 5 is a right side view of the pole climbing and fall restraint device positioned around a pole;

FIG. 6 is a top view of the pole climbing and fall restraint device positioned around a pole, the hooks being in an outwardly extended position to show the features of the hooks; and,

FIG. 7 is a bottom view of the pole climbing and fall restraint device positioned around a pole, the hooks being in an outwardly extended position to show the features of the hooks.

The crimps shown in broken line in FIGS. 1, 2, 5, 6 and 7 as well as the pole shown in broken line in FIGS. 2-7 form no part of the claimed design.
